(57) **CLAIM**

The ornamental design for an adjustable arm magnetic mount, as shown.

DESCRIPTION

FIG. 1 is a perspective view of an adjustable arm magnetic mount showing the new design

FIG. 2 is a top right view thereof

FIG. 3 is a right side view thereof

FIG. 4 is a left side view thereof

FIG. 5 is a front view thereof

FIG. 6 is a rear view thereof

FIG. 7 is a top view thereof; and,

FIG. 8 is a bottom view thereof.

The broken lines shown in the drawings illustrate portions of the adjustable arm magnetic mount that form no part of the claimed design.

1 Claim, 8 Drawing Sheets
